CLAIM

The ornamental design for a surface-mountable holder for a plurality of desk trays, as shown and described.

DESCRIPTION

FIG. 1 is a front elevational view of a surface-mountable holder for a plurality of desk trays showing my new design;

FIG. 2 is a rear elevational view;

FIG. 3 is a left side elevational view, the right side being a mirror image thereof;

FIG. 4 is a top plan view;

FIG. 5 is a bottom plan view thereof; and,

FIG. 6 is a front, top perspective view thereof.

FIG. 1

FIG. 2

FIG. 5

FIG. 4

FIG. 6
